OTHER PUBLICATIONSEM 1314322-00001 Registered Design, (Calor) Feb. 20, 2012, [online], [retrieved on Jul. 24, 2013] Retrieved from the Community Design Database of the Office for Harmonization in the Internal Market using the Internet: URL: <http://oami.europa.eu>.*Primary Examiner* — Keli L Hill(74) *Attorney, Agent, or Firm* — Sutherland Asbill & Brennan LLP(57) **CLAIM**

The ornamental design for a “water removing hair brush,” as shown and described.

DESCRIPTION

FIG. 1 is a front, right side, and bottom perspective view of my new design for a hair brush.

FIG. 2 is a front view of the hair brush shown in FIG. 1.

FIG. 3 is a rear view of the hair brush shown in FIG. 1.

FIG. 4 is a right side view of the hair brush shown in FIG. 1, the left side view being a mirror image thereof.

FIG. 5 is a top view of the hair brush shown in FIG. 1.

FIG. 6 is a bottom view of the hair brush shown in FIG. 1.

FIG. 7 is a front, right side, and bottom perspective view of another embodiment of my new design for a hair brush.

FIG. 8 is a front view of the hair brush shown in FIG. 7.

FIG. 9 is a rear view of the hair brush shown in FIG. 7.

FIG. 10 is a right side view of the hair brush shown in FIG. 7, the left side view being a mirror image thereof.

FIG. 11 is a top view of the hair brush shown in FIG. 7; and, FIG. 12 is a bottom view of the hair brush shown in FIG. 7.

The broken lines shown are included for the purpose of illustrating portions of the water removing hair brush that form no part of the claim.
